UNITED STATES PATENT OFFICE.

RALPH HENRY POWERS, OF PORT HURON, MICHIGAN.

AUTOMATIC SCREEN FOR WINDOWS.

1,263,285.

Specification of Letters Patent. Patented Apr. 16, 1918.

Application filed May 24, 1917. Serial No. 170,718.

To all whom it may concern:

Be it known that I, RALPH H. POWERS, a citizen of the United States, and a resident of Port Huron, in the county of Saint Clair 5 and State of Michigan, have invented a certain new and useful Improvement in Automatic Screens for Windows, of which the following is a specification.

The present invention relates to window 10 screens and has for an object to provide a screen for attachment to the top or bottom or both of a window, and to be engaged with the one or more sashes therein for screening the opening through the window when 15 the sash is moved into open position.

Another object is to provide a screen of the roller type which is spring actuated to withdraw the screen into a casing or the like out of the way when not in use, and to expose 20 only a portion of the screen sufficient to block the opening in the window to the passage of insects, flies and the like.

A further object of the invention is to provide means for guiding and retaining 25 the adjustable screen in close fitting engagement with the window at all adjustments of the screen with the sash, which retaining means is adjustable to accommodate windows varying within practical limits in 30 width so that the automatic screen of this invention may be applied to practically all types of windows now in common use.

The above, and other objects and advantages of this invention will be in part described, and in part understood, from the 35 following detailed description of the present preferred embodiment, the same being illustrated in the accompanying drawings, wherein:

40 Figure 1 is an outer side elevation of a window having automatic screens constructed according to the present invention applied to the top and bottom thereof.

Fig. 2 is a fragmentary, enlarged, vertical section taken through the lower portion 45 of a window having the automatic screen applied thereto.

Fig. 3 is a fragmentary side elevation of a lower corner of a window, showing the 50 screen applied thereto.

Fig. 4 is a horizontal section through the same.

Fig. 5 is a fragmentary inner side elevation 55 of the end of the screen as attached to the lower bar of a sash.

Fig. 6 is a detail enlarged transverse section taken through the screen sections, showing the spring therein for re-winding the screen, when the latter is relaxed by the placing of the sash. 60

Fig. 7 is a detail enlarged view of the screen roller, showing a means for fastening the inner edge of the screen to the roller.

Fig. 8 is a fragmentary enlarged section taken vertically through the lower portion 65 of a window casing and a sash in closed position, showing the screen casing and the screen in position.

Fig. 9 is a fragmentary view of a section of the flexible screen and frame therefor, 70 showing a modification in the structure thereof.

Fig. 10 is a horizontal section through the same and through a modified form of guide 75 thereof.

Fig. 11 is a detail perspective view of one of the guide rails for the screen.

Fig. 12 is a fragmentary plan view of the lower end of the modified form of screen, enlarged, showing the flaring mouth of the 80 guiding groove in the screen frame.

Fig. 13 is a transverse section through the lower portion of a window casing, showing a modified construction and mounting 85 of the screen casing.

Fig. 14 is a detail perspective view of a section of the modified form of screen, showing the hinged joint between the sections thereof.

Referring to these drawings, wherein like 90 parts are designated by similar characters of reference throughout the several views, 10 designates a casing which may be formed from sheet metal and which is secured at its base portion upon the inner sillstrip 95 A of the window, and which is preferably flush at its outer closed side with the outer edge of the strip A. The casing 10 is provided with a longitudinally extending opening in its top adjacent to its outer side 100 through which the flexible screen of the invention is adapted to extend.

The casing 10 is provided therein with a longitudinally extending roller 11 about which the screen is adapted to be rolled, the latter being secured to the roller 11 by the provision of an attaching strip 12, as shown in Fig. 7, which clamps the inner edge of the wire meshing portion of the screen longitudinally against one side of the roller 11. 110

The wire mesh portion 13 of the screen is reinforced and held in position at its opposite edges by the provision of a flexible frame, the same comprising series of hingedly connected blocks 14 transversely registering and adapted to be rolled upon the roller 11.

The outer free end of the wire mesh body 13 is provided with an attaching strip 15 having a series of transversely elongated slots 16 adapted for insertion over turn-buttons 17 which are placed upon the lower bar of the sash B of the window. The roller 11 is normally urged in turn in a direction to wind the flexible screen thereabout by means of a spiral spring 18 located in one end of the casing 10. One end of the spring 18 is secured by rivets or the like to the roller 11, and the opposite end of the spring 18 is secured to the casing 10. When the sash B is raised, the flexible screen is drawn out of the casing and unwound from the roller 11 to an extent sufficient to close the opening between the casing 10 and the adjacent bar of the sash B.

The flexible frame of the screen is held in close contact with the opposite sides of the window by the provision of a pair of guide-rails 19, the same being of channel form and having the grooves thereof facing inwardly opposite one another, and being of a size to freely receive the block 14 of the flexible frame therein. The guide rails 19 are provided with laterally extending flanges 20 throughout the length of the rails 19 adapted to bear against the inwardly extending flanges of angle-irons 21 which are secured, by screws or the like, against the inner opposite sides of the window casing. The said flanges of the angle-irons 21 project inwardly toward each other, and are adapted to lie against the guide rails of the sash B when the latter are in position. The flanges 20 of the guide rails 19 and the abutting flanges of the angle-irons 21 are provided with transversely extending elongated slots adapted to receive retaining bolts 22 therethrough which are preferably countersunk in the inner faces of the angle-irons 21 and provided upon their outer ends with wing nuts 23 or the like for binding the guide rails 19 in adjusted position upon the angle-irons 21 when the guide rails 19 are moved taut and from each other into the desired adjusted position. By thus adjustably mounting the guide rails 19, the latter may be accommodated to screens varying in width and to windows of various sizes. The guide rails 19 thus hold the lateral edges of the flexible screen from bulging outwardly from the window casing, and seal the spaces between the flexible screen and the casing.

It is of course understood that the automatic roller screen thus far may be applied

to the top of the window casing and attached to the top bar of the upper sash thereof, as shown in Fig. 1, so that the flexible screen is drawn downwardly when the upper sash is moved into open position. In this instance, the guide rails 19 are arranged about the outer side of the window casing to hold the flexible screen from bulging outwardly, and for sealing the spaces at the opposite edges of the screen.

In the modification disclosed in Figs. 9, 10, 11, 12, and 14, the side bars of the frame of the flexible window screen are composed of pivotally connected blocks 14^a having in their outer sides, a vertically extending groove 24 which, as shown in Fig. 12, flares at the lower end of the lowermost block 14^a to provide an entering throat 25. The blocks 14^a are adapted to fit between the flanges 26 and 27 of opposed guide rails which are mounted upon the angle-irons 21 secured to the inner opposite sides of the window casing. It will be noted from Fig. 10 that in each instance, the outstanding flanges 28 of the guide rails 90 lap over against the inner sides of the angle-irons 21, and that the flanges 26 are adapted to lie close against the opposed and lower bars of the window sash.

The wire mesh body of the modified form 95 of screen is preferably made up of a plurality of transversely extending sections 29, one section for each opposite pair of blocks 14^a. The sections 29 are not adapted to flex about the roller when wound and as 100 shown in Fig. 14, are hingedly connected together by links 30 which lie closely together and complete the wire mesh body portion of the screen. These links 30 admit of the rolling of the screen body about the roller 105 and are bent or hinged in the transverse plane of the hinged connection of the block 14.

In Fig. 13, the window casing is provided with space-apart strips 31 and 32 and an inner facing strip 33, the strips and the sides of the window casing forming an enclosure or boxing adapted to receive the casing 10^a of the roller screen. The top strip 31 is provided with an aperture through which the flexible screen is adapted to extend, the screen being attached to the sash of the window in the manner above described.

It is of course understood that various other changes and modifications may be made in the details of construction and design of the above specifically described embodiment of the invention without departing from the spirit thereof and being restricted only by the scope of the following claims.

I claim:

1. In a screen adapted for application to windows having sliding passes therein, a normally retracted flexible screen body 130

adapted to be mounted at one end of the casing, attaching means upon the free end of the strip for engagement with the sash to secure the screen body thereto, a pair of supporting members secured against the inner opposite sides of the window casing, and including inwardly extending flanges, a pair of guide rails for engagement against the opposite edges of the flexible screen body to retain the latter in position when extended, said guide rails being provided with outstanding flanges adapted to overlap the flanges of said support, and means for adjustably clamping said overlapping flanges together to accommodate the guide rails within window casings varying in width.

2. In a window screen, the combination of a casing, a roller mounted in said casing, a spring carried in said casing and engaging the roller to urge the same to turn in one direction, a flexible screen body mounted on the roller and extending at one end through the casing, series of hingedly connected blocks secured along the opposite edges of the screen body adapted to be rolled therewith upon the roller within the casing, and a pair of guide rails carried within the window casing and adapted to engage said pivotally connected blocks, to retain the same and the screen body from bulging in either direction.

3. In a screen as specified, the combination of a roller, a flexible screen body rolled upon the roller, attaching means connected to the outer end of the flexible body for securing the same to the shaft of a window, opposed series of hingedly connected blocks carried at the opposite lateral edges of said flexible screen body, a pair of guide rails adapted to be secured against the inner opposite sides of a window casing, adapted to receive said pivotally connected blocks therein, and means for adjusting the guide rails toward and from each other to seal the spaces at the opposite edges of the flexible screen body and the adjacent sides of the window casing.

4. In a screen as specified, the combination of a flexible screen body adapted to be mounted at one end of a window casing,

means for normally retracting the screen body toward said end of the casing, opposed series of pivotally connected frame blocks secured along the opposite edges of said flexible screen body, a pair of channeled guide rails mounted in the inner opposite sides of the window casing and adapted to slidably receive therein said blocks, and adjustable supporting means for the guide rails to seal the space between the same and adjacent sides of the casing and to accommodate the guide rails to screen bodies varying in width.

5. A screen for application to windows having sliding sash therein, comprising a flexible body member, a roller adapted to support one end of the body, a spring connected to said roller to urge the same normally in one direction, for rolling the flexible body thereabout, attaching means upon the outer end of the flexible body for engaging with said sash, and adjustable guides carried upon the window casing adapted to be advanced toward each other for engagement with the opposite edges of the flexible screen to retain the same in close fitting engagement with the casing.

6. In a screen as specified, the combination of a flexible screen body, means for normally retaining the screen body in a rolled position, said screen body being adapted to be mounted at one end of the window casing, an attaching strip connected to the outer end of said screen body for engagement with the adjacent bar of a sash, series of pivotally connected blocks arranged at the opposite sides of the flexible screen body and provided with longitudinally extending grooves in one side thereof, a pair of guide rails adapted to be mounted in the inner opposite sides of a window casing and having spaced-apart flanges adapted to receive said series of blocks therebetween, one of said flanges being provided with a tongue upon its inner side adapted to seat in said groove of each series of blocks to retain the latter from displacement inwardly by the bulging of the flexible screen body.

RALPH HENRY POWERS.
